UNITED STATES PATENT OFFICE.

LAWRENCE E. GUIGNON AND ERNEST E. GUIGNON, OF CORRY, PA.

BARREL-PUMP.

SPECIFICATION forming part of Letters Patent No. 286,428, dated October 9, 1883.

Application filed March 29, 1883. (Model.)

To all whom it may concern:

Be it known that we, LAWRENCE E. GUIGNON and ERNEST E. GUIGNON, both of Corry, in the county of Erie and State of Pennsylvania, have invented a new and Improved 5 Barrel-Pump, of which the following is a full, clear, and exact description.

The object of this invention is to provide a barrel-pump that shall be cheap and practical, 10 and one having such construction that a separate drip-pipe for leading the drip from the tray back into the barrel will not be required.

Reference is to be had to the accompanying drawings, forming part of this specification, in 15 which similar letters of reference indicate corresponding parts in all the figures.

Figure 1 is a sectional elevation of our new and improved barrel-pump as it appears when applied to a barrel for use. Fig. 2 is a plan 20 view of our invention. Fig. 3 is a perspective view of the brace for the tray, detached from the device; and Fig. 4 is a detailed inverted plan view of a portion of the bottom of the tray.

A represents the tray for holding the measures or vessels to be filled, the bottom B of 25 which tray is made conical, so that the drain will be from center to circumference. Near the edge of the tray the bottom B is provided with the short pipe or tube C, through which 30 the pump-tube D passes, and through which, also, the drip finds its way from the tray back into the barrel or cask J, to which the device is applied, thus avoiding the use of a separate drip-pipe, as is commonly used with devices 35 of this kind.

The device is attached to the barrel or cask by means of the bung-tube E, within the upper end of which the said short tube C fits, which bung-tube is made conical at its lower 40 end, as shown at d, to fit snugly in the bung-hole of the barrel or cask, as will be understood from Fig. 1.

F is a detachable brace, formed at one end with the sleeve f, that fits upon the bung-tube 45 E, and at the other with the cross-piece f', that fits in the channel b, formed or secured upon the bottom B of the tray A, which brace and cross-piece serve to support the tray, and also to prevent vibration of the tray while the 50 plunger G is being operated in the pump-tube D. The pump-tube D and plunger G are of

ordinary construction, except that the tube D is provided at the bottom with the sharp points a, that are adjusted to be embedded into the material of the barrel or cask, for staying the 55 bottom of the pump-tube and steadyng the device while pumping.

The guard H, placed in the tray A, is of ordinary construction, being composed of the rim h, center piece, h', and radial rods h'', and 60 is for the purpose of preventing articles from falling upon the bottom of the tray.

Constructed in this manner the device is made practical, and is cheaper and simpler than those heretofore produced, and is held firm 65 and steady while the pump is being operated; and by making the brace F detachable and the tube C to fit removably within the bung-tube E, it will be seen that the device may be taken all apart for storing away or for trans- 70 portation.

We are aware that a bung and sleeve for holding a pump in a barrel are the subject of a re-issued Patent No. 5,198; but that is a screw-threaded bung, the sleeve is a funnel, and is 75 not a part of the bung, and we do not claim the same as our invention.

Having thus described our invention, what we claim as new, and desire to secure by Letters Patent, is—

1. The combination, with a barrel-pump, of a convex-bottomed drip-pan having a hole through said bottom, near one edge thereof, to receive the pump loosely, a sleeve secured to the under side of the pan around said hole, and 85 a guard consisting of a circular plate, radial wires extending therefrom to a circular rim adapted to rest in the edge of the pan, and to hold said plate above the apex of the convex bottom, as shown and described, whereby a 90 measure may be held in a vertical position to be filled level full beneath the pump-spout, and a drip-pan of small dimensions is adapted to return the overflow to the barrel, as specified.

2. In a barrel-pump, the brace F, made detachable from the tube E and tray A, substantially as and for the purposes set forth.

3. The combination, with the tray B and the bung-tube E, of the brace F, having sleeve f and cross-piece f', substantially as and for the 100 purposes set forth.

4. The combination, with a barrel-pump, of

a dripping-tray having a hole through it, and a sleeve or tube around the hole projecting from the lower side of the tray, and a tube fitting said sleeve externally, the lower end of the latter tube having its exterior shaped like a bung, adapted to fit the bung-hole of a barrel, as shown and described.

5. The tray A, provided with the channel b, in combination with the brace F, having the cross-piece f', substantially as and for the purposes set forth.

6. The tray A, bung-tube E, and brace F, made detachable, whereby they may be taken apart, substantially as and for the purposes set forth.
